UNITED STATES PATENT OFFICE

159,692

ELECTRIC FAN OR SIMILAR ARTICLE

Alfons J. Steinhart, West Springfield, Mass., assignor to Son-Chief Electrics, Incorporated, Winsted, Conn., a corporation of Connecticut

Application October 11, 1949, Serial No. 5,424

Term of patent 14 years

(Cl. D26—7)

To all whom it may concern:

Be it known that I, Alfons J. Steinhart, a citizen of the United States, residing at West Springfield, in the county of Hampden and State of Massachusetts, have invented a new, original, and ornamental Design for an Electric Fan or Similar Article, of which the following is a specification, reference being had to the accompanying drawing, forming part thereof, in which—

Fig. 1 is a front elevational view of an electric fan, showing my new design, the disclosure being fragmentarily shown for convenience of illustration;

Fig. 2 is a side elevational view thereof; and

Fig. 3 is a top plan view of the base, the remainder of the electric fan being omitted for convenience of illustration.

The dominant features of my design reside in that portion shown in full lines in the drawing.

I claim:

The ornamental design for an electric fan or similar article, substantially as shown and described.

ALFONS J. STEINHART.
